(57) CLAIM

The ornamental design for a tub and shower cleaning tool, as shown and described.

DESCRIPTION

FIG. 1 is a perspective view of a tub and shower cleaning tool showing the new design;

FIG. 2 is a left side view thereof, the right side view thereof being a mirror image of the left side view shown;

FIG. 3 is a top view thereof;

FIG. 4 is a bottom view thereof;

FIG. 5 is a front view thereof; and,

FIG. 6 is a rear view thereof.

The broken lines in the drawings are shown for illustrative purposes only and form no part of the claimed design. In addition, the surface shading illustrated in the drawings is provided merely to highlight the contour of design; it is not intended to be illustrative of texture or gloss.
